UNITED STATES PATENT OFFICE.

WILLIAM FLOCKTON BROWNELL, OF NEW LONDON, WISCONSIN.

HERNIAL-TRUSS SUPPORT.

SPECIFICATION forming part of Letters Patent No. 670,530, dated March 26, 1901.

Application filed August 21, 1900. Serial No. 27,594. (No model.)

To all whom it may concern:

Be it known that I, WILLIAM FLOCKTON BROWNELL, a citizen of the United States, residing at New London, in the county of Waupaca and State of Wisconsin, have invented 5 certain new and useful Improvements in Truss Holders or Supports; and I do declare the following to be a full, clear, and exact description of the invention, such as will enable others skilled in the art to which it appertains to make and use the same.

My invention relates to improvements in truss-pad holders or supports, and has for its object to provide a simple and effective device of this character adapted to hold the pad firmly and securely against movement and yet permit of its ready adjustment or detachment when desired.

The invention consists of a pad-holder embodying certain novel features of construction, combination, and arrangement of parts, which will be hereinafter more fully described, and particularly pointed out in the appended claims.

25 In the accompanying drawings, Figure 1 is a perspective view of a pad-holder constructed in accordance with my invention. Fig. 2 is a sectional view thereof, and Fig. 3 is a detail view of the clamping-block.

30 Like reference characters designate corresponding parts throughout the several views.

A represents the holder, which consists of a circular plate or disk B, provided with a series of openings c for passage of fastening devices for securing it to the pad-base. The outer side or face of this holder is convex and provided with teeth or serrations d. A threaded stem or post e projects outward from the center of the convex side of the disk and is adapted to receive a clamping-block F and jam-nut g. This block F is provided with an elongated or elliptical opening h, which receives the post, and a transverse notch i in its under side near one end and intersecting the opening h, the wall of said notch being formed with teeth or biting projections j. The outer end of the block is formed into a curved finger-piece k, whereby the block may be conveniently handled and adjusted.

50 In use the pad is secured to the disk B by

means of screws or other suitable fastening devices passed through the openings c, and the fastening band or wire l is then extended transversely between the plate and clamping-block through the notch i. The block is then 55 properly adjusted to bring the wire in position and the jam-nut tightened. When this is done, the band or wire is clamped firmly between the block and disk and the pad is held securely against slipping by the serrations d and teeth j, which bite into the wire and prevent independent movement of either of the parts. To adjust the pad, it is simply necessary to loosen the jam-nut, move the block outwardly, move the pad to the desired 65 position, and then tighten the jam-nut to cause the block to clamp the wire.

The device is simple of construction and by its use adapts the pad to be readily and conveniently applied, removed, and adjusted 70 and insures a firm retention of the pad in its proper operative position.

Having thus described my invention, what I claim, and desire to secure by Letters Patent, is—

75

1. A holder or support for truss-pads, comprising a plate or disk, a stem or post projecting from the disk, a clamping-block having an opening for the passage of the post and a notch to receive a suspending band or wire, 80 and a nut on the post to clamp the block, substantially as described.

2. A holder or support for truss-pads, comprising a disk having an outer convex serrated face and a threaded stem or post projecting therefrom, a clamping-block having an opening to receive the post, a notch in its under side to receive a suspending band or wire, the wall of said notch being formed with biting projections, and a finger-piece, and a 85 nut on the post to clamp the block, substantially as described.

In testimony whereof I have hereunto set my hand in presence of two subscribing witnesses.

WILLIAM FLOCKTON BROWNELL.
